UNITED STATES PATENT OFFICE.

GEORGE B. HOAG, OF CLEVELAND, OHIO.

SHEET-PILING.

1,052,251.

Specification of Letters Patent.

Patented Feb. 4, 1913.

Application filed June 4, 1912. Serial No. 701,531.

To all whom it may concern:

Be it known that I, GEORGE B. HOAG, a citizen of the United States, a resident of Cleveland, county of Cuyahoga, and State of Ohio, have invented a new and useful Improvement in Sheet-Pilings, of which the following is a specification, the principle of the invention being herein explained and the best mode in which I have contemplated applying that principle, so as to distinguish it from other inventions.

My invention relates to sheet-piling, and has for its object the provision of sheet-piling elements which when assembled will form a tight sheet sufficiently impervious to water and quicksand for practical use and in which each element is of light weight, cheap in construction and durable, so as to be capable of continued and indefinite use.

My said invention consists of means hereinafter fully described and particularly set forth in the claims.

The annexed drawing and the following description set forth in detail certain means embodying the invention, the disclosed means, however, constituting but one of the various mechanical forms in which the principle of the invention may be applied.

In said annexed drawing: Figure 1 is a front elevation of a fragmentary portion of sheet-piling embedded in earth, and embodying my invention. Fig. 2 is an end elevation of one of the said piling elements, showing the contiguous earth. Fig. 3 is a horizontal section, on an enlarged scale, of a fragmentary portion of the piling.

Each element of the illustrated piling embodying my invention comprises a main or body portion A, made preferably of wood planking of the usual character, and two facing-strips B and C. One of these strips, B, is made of channel steel, and is secured to one of the two opposite sides of smaller dimension, by means of spikes or screws D passing through suitable countersunk openings b, with the flanges b' and b'' of the channel projecting outwardly. The other of the two strips, C, is of segmental cross-section, and is secured to the other of said two opposite faces by means of spikes or screws also passing through countersunk openings c, with the curved side of the strip upon the outside, as shown.

The facing-strips of similar cross-section are, of course, all made of material having the same dimensions, and the segmental

strips are preferably of such dimensions that when laid in the channels, they will simultaneously engage the web and flanges of the latter, as shown in Fig. 3.

In assembling the piling, the elements are laid so that a strip C will engage a strip B in the manner above described. In thus obtaining three lines of contact, a joint is obtained which will practically exclude water and quicksand, which is the desired end to be obtained. The dimensions of the strips C may, however, be made such that they engage only the flanges, and I have found that the two lines of contact thus secured, in some cases, answer the purpose. Continued use may, in this last described form, eventually, wear the two engaging strips so that three lines of contact will ultimately be obtained.

While other forms of facing-strips may be used without departing from the spirit of my invention, I find the use of channels and segmental strips permit me to take advantage of material of stock form or standard cross-section and size, a circumstance which materially contributes to the cheapness of my construction without in any way depreciating its practical value.

Furthermore, my above described form of piling, on account of the use of wood for the body-portion, is of minimum weight, consistent with the required strength, and hence may be handled with facility and economy.

Having fully described my invention, what I claim and desire to secure by Letters Patent is:

1. A sheet-piling element consisting of a wooden strip of substantially rectangular cross-section and having secured respectively upon the two opposite sides, metal facing-strips, one of the latter being of channel formation, and the other being of a form such as would lie within such channel.

2. A sheet-piling element consisting of a wooden strip of substantially rectangular cross-section and having secured respectively upon the two opposite sides, metal facing-strips, one of the latter having a channel-like cross-section and the other having a segmental cross-section.

3. In sheet-piling, the combination of two adjacent sheet-piling elements each of whose main or body portions is formed of wood, and whose contiguous sides are provided

respectively with a channel facing-strip and a facing-strip having a segmental cross-section, such latter strip being in contact with that face of the web of the channel-strip 5 between the latter's flanges.

4. A sheet-piling element consisting of a wooden strip of substantially rectangular cross-section and having secured on one of the two opposite sides a facing-strip of 10 channel formation with the flanges projecting outwardly; and upon the other of said two faces, a facing-strip of such form as is adapted to simultaneously engage, when laid in said channel-strip, both flanges of 15 the latter.

5. A sheet-piling element consisting of a wooden strip of substantially rectangular cross-section, and having secured on one of the two opposite sides a facing-strip of channel formation with the flanges projecting outwardly; and upon the other side of 20 said two faces a facing-strip of such form as is adapted to simultaneously engage, when laid in said channel-strip, the web and both flanges of the latter.

Signed by me this 28th day of May, 1912.
GEO. B. HOAG.
